ATTORNEY

UNITED STATES PATENT OFFICE.

LEWIS H. McCARRON, OF SIERRA MADRE, CALIFORNIA, ASSIGNOR TO ELECTRIC SIGN FLASHER CORPORATION, OF LOS ANGELES, CALIFORNIA, A CORPORATION OF CALIFORNIA.

ELECTRIC-CIRCUIT CONTROLLER.

Application filed April 28, 1926. Serial No. 105,095.

My invention relates to mechanism for making and breaking electric circuits whereby an intermittent use of the electric current is provided and the object thereof is to provide a simple and reliable mechanism for that purpose.

The drawing forming a part of this application is a diagrammatic representation of my improved mechanism.

10 Wire 1 is the positive or feed wire and is connected to a source of electricity shown as battery A. Wire 1 runs to and is connected to contact 2 which is carried by spring 3 that is carried by lever 4 but is insulated therefrom which is pivoted by pin 5 on a suitable support or back plate 6 of insulating material. Contact 2 normally engages contact 7 mounted on lever 8 which is also pivotally mounted on plate 6 by pin 5. A thermo-expansive wire 9 is connected to lever 8 between contact 7 and pin 5 at a point near the pin. Wire 9 runs at the side of lever 4 and is connected to an adjusting screw 10 mounted in bearing 11 secured to plate 6. Block 11 is connected by wire 12 with the winding of magnet 13 from which winding leads the return wire 14. Wire 15 leads to the device to be supplied with an interrupted current and wire 16 is the return wire therefrom. When current is supplied to wire 1 it passes through contacts 2 and 7, lever 8, wire 9, screw 10, block 11, wire 12, windings of coil 13 and wire 14 thereby energizing coil 13 which then draws the end of lever 4 which forms an armature away from stop 17. Stop 17 is mounted on plate 6, thereby causing contacts 2 and 8 to remain longer in engagement than would be the case if lever 4 were not rockable. The current soon heats wire 9 and it expands. A spring 18 keeps wire

9 taut as it expands. As soon as the expansion of wire 9 permits spring 18 to draw contact 8 away from contact 2 the current is broken and wire 9 begins to cool and shorten and coil 13 is de-energized.

Spring 19 which is connected to lever 4 and to plate 6 draws lever 4 back to stop 17 thereby increasing the time of the separation of contacts 2 and 8. The length of time that the current is off or on can be regulated by screw 10 and stop 17. If desired, contact 2 could be stationary.

By this construction a simple and efficient mechanism is provided for controlling an intermittent electric circuit in which there are no parts to wear out or to get out of order.

Having described my invention, I claim:

An electric circuit controller comprising a back plate of insulating material; a lever rockably mounted on said plate; an upper lever rockably mounted on said plate intermediate its ends, one end of said lever forming an armature; contacts carried by said levers, said contacts being normally in engagement; springs connected to said levers to normally cause the contacts to separate; an electro magnet mounted on said plate so positioned that the upper lever forms an armature therefor; a bearing on said plate electrically connected to said magnet; an adjusting screw in said bearing; a thermo-expansive wire connected to said screw and to said lower lever; and an adjustable stop on said plate adapted to regulate the movement of said armature.

In witness that I claim the foregoing I have hereunto subscribed my name this 16th day of April, 1926.

LEWIS H. McCARRON.
